Groh Beeler

ATTORNEY

UNITED STATES PATENT OFFICE.

RUSSELL B. CRESSMAN, OF PHILADELPHIA, PENNSYLVANIA.

ELECTRIC-LAMP INDICATOR.

Application filed July 2, 1923. Serial No. 649,099.

To all whom it may concern:

Be it known that I, RUSSELL B. CRESSMAN, a citizen of the United States, residing at Philadelphia, in the county of Philadelphia and State of Pennsylvania, have invented certain new and useful Improvements in Electric-Lamp Indicators, of which the following is a specification.

This invention relates to electric lighting fixtures or appliances and has particular reference to the use of incandescent electric lamps.

It being well understood by those versed in the art that an electric lamp (meaning by this term an electric lamp bulb as a unit) may glow freely and give satisfactory white appearance and light for a certain number of hours, but thereafter the light becomes gradually yellowish, due to the increase in the red and yellow light rays, and correspondingly dimmer and less efficient, even though the consumption of electricity may not be reduced in proportion to the efficiency of the lamp. In other words, I have observed that electric lamps should be discarded and replaced much more frequently than they are, largely due either to carelessness or to the inability for the owner or user of the lamps to determine with a reasonable degree of accuracy the time when the lamp should be discarded. This latter condition obtains especially in connection with the modern practice of sealing the lamps by means of globes or reflectors pertaining to the indirect or semi-indirect lighting system, now commonly practiced, especially in connection with the high powered type of lamps.

Among the objects of my invention, therefore, is to provide an indicator having the adaptability of enabling any person to observe with facility and substantial accuracy the critical period in the life of the lamp, that time or period when the lamp is no longer efficient or giving a full equivalent in the quantity or color of the light for the electricity consumed thereby.

Another object of the invention is to provide what may be termed a combined globe and indicator so constructed as to serve the usual purposes of a globe or light diffuser and an indicator of the condition of the lamp.

In carrying out the foregoing and other allied objects of the invention reference is

made to the accompanying drawing which shows one practical embodiment of the invention.

10 indicates an electric lamp in a socket 11 constituting a part of a ceiling fixture 60 12. Surrounding said lamp and secured to the fixture is a globe 13 of any suitable size, design, or construction, ordinarily, however, made of glass or the like, and of a translucent nature for the purposes already al- 65 luded to, including the diffusion of the intense light from the lamp and serving as an indicator of the condition of the lamp.

In carrying out this invention and discovery in a practical form I construct the 70 globe of material having a color or tint of such a character as to compel the light in passing outward therethrough to be perfectly white and so resemble natural daylight. For this purpose I preferably em- 75 ploy a blue tint for the globe, the depth of the color or tint being predetermined, however, for the special purpose now about to be more precisely set forth. After a long series of experiments I have discovered that 80 the depth or quality of tint of a lamp globe may be so determined that the light emitted therefrom will be substantially pure white throughout the entire period of efficient usefulness of the lamp, and then at the end 85 of such period, or what has been referred to herein as the critical time, the light emitted from the globe will be of a pronounced or decidedly yellow or muddy hue. That is to say, the light from my improved indicator devices will appear either efficiently 90 white or inefficiently yellow, so that any observer may note readily the condition of any lamp as to its condition of efficiency 95 by simply observing the appearance of the globe 13.

I am aware that it is not new practice to make lamp bulbs or globes of colored glass or to employ a tint of blue or any other well known color in such constructions, such 100 tint or color being employed ordinarily for both the reduction of the effective strength of the lamp and the modification of the color of the light, but I believe it is new with me to provide a lamp globe in which 105 the color employed is of such a character or quantity as to be directly correlated to the period of efficiency of the lamp to be employed therein so that the critical period will be indicated automatically and directly 110

by the globe itself. It being common knowledge in the glass working art how to make a blue layer in the glass or to tint the glass with blue or other suitable coloring in various degrees of density, I wish to disclaim any general claim for a monopoly on the idea of tinting glass or to employ a tinted glass in connection with an electric lamp. On the contrary, I wish to insist that this invention is more in the nature of a discovery wherein I have discovered or ascertained that the intensity of the color in the glass may be so correlated to the intensity of the electric lamp light as to produce the effect herein set forth. In the practice of this discovery the amount of blue or other suitable color in the glass 13, no matter by what chemical or mechanical process it is so supplied, is sufficient to kill the red and yellow rays of the lamp during and only during that critical period of usefulness of the lamp when it is calculated to produce an efficiently white light. The light itself is never blue because there is not sufficient blue tint or color in the glass. The amount of color in the glass is just enough, dependent upon the strength of the lamp, so that the light turns yellow or muddy in color practically immediately when the time of use of

the lamp has reached the critical time or period, the time when its usefulness is no longer efficient. For these reasons it is maintained that the invention or discovery is in the nature of an indicator of the period of usefulness of the lamp, rather than in the general idea of making a tinted lamp globe.

I claim:

1. The combination with an electric lamp having a substantially predetermined period of illuminating efficiency, of a combined globe and indicator therefor having a color component of a quality and depth sufficient to serve to emit substantially white light from the lamp during such period aforesaid and then to show a distinctly different character of light at the end of such period.

2. The herein described electric lamp indicator consisting of a glass globe of tinted composition of predetermined depth through which light is designed to pass and be made to appear substantially white for a predetermined time, according to the period of efficient usefulness of the lamp producing the light, and then to indicate directly and automatically by a different color of light that the period aforesaid has passed.

In testimony whereof I affix my signature.
RUSSELL B. CRESSMAN.
